UNITED STATES PATENT OFFICE.

HOMER J. WADDELL, OF BALTIMORE, OHIO.

GAS METER.

Substitute for application Serial No. 688,141, filed January 24, 1924. This application filed December 4, 1925. Serial No. 73,263.

The present invention is directed to improvements in gas meters and particularly to wet-gas meters.

An object of the invention is to provide a meter so constructed that the drum thereof can be removed from the casing to permit repair or adjustment of the parts in an easy and convenient manner.

The crowns of meters of this type heretofore have been bolted to the interior of the casing and are associated in such way with the drum that it is necessary to remove the crowns to permit the removal of the drum and this invention has been perfected to overcome this disadvantageous condition.

A further object of the invention is to provide a casing so constructed that the incoming gas, which as well known is of substantially the same temperature the year around, will retain the sealing oil in substantially the same fluidity, thereby permitting the device to operate in an even manner.

With these and other objects in view, as will appear as the description proceeds, the invention consists in the novel features of construction, combinations of elements and arrangements of parts, and hereinafter to be fully described and pointed out in the appended claims.

In the accompanying drawing:

Figure 1 is a vertical sectional view through the device,

Figure 2 is a sectional view on line 2—2 of Figure 1,

Figure 3 is a sectional view on line 3—3 of Figure 1, and

Figure 4 is a vertical sectional view showing a modified form of the invention.

Referring to the drawings 1 designates the casing, the lower portion 2 of which is circular in cross-section and the upper portion 3 is oval in cross section so that said casing will produce a net appearance.

Located in the casing 1 is a sealing oil container 4, the wall of which is spaced from the wall of the lower portion 2 of the casing 1 by the web 3' to produce an annular gas receiving chamber 5. The bottom 6 of the container 4 is spaced above the bottom of the casing 1 and is concavo-convex in cross-section so as to produce a comparatively large compartment 7 for the reception of grit or any foreign matter which may enter the casing 1 with the gas, this foreign matter will

obviously collect in the compartment 7 and will not enter the valve structure.

Upon the convex or upper surface of the bottom 6 is a plurality of circularly aligned hollow oil breaking crowns 8, preferably six in number, said crowns being substantially rhomboidal in cross-section and have their lower ends welded or soldered to the bottom 6.

Rising from the vertex of the bottom 6 is a gas conducting tube 9 and supported thereby is a universal coupling 10 which in turn is connected to the fluid distributing valve connecting mechanism 11 and, since this mechanism is well known a detail description thereof is not thought necessary. As customary this valve mechanism supports the usual casing 12 which surrounds the tube 9.

The drum 13 includes a plurality of measuring pockets 14 corresponding in number to the crowns 8 and as usual these pockets successively communicate with the tube 9 through the valve ports 15 in a well known manner to permit the gas to flow in measured quantities to its point of use.

Heretofore the crowns 8 have been bolted within the casing and are of such dimensions that it was necessary that they be released or unbolted before the drum could be removed from the casing.

To overcome this annoyance I have permanently secured the crowns 8 to the bottom 6 of the container 4 and it will be observed that the diameter of the openings 16 of the drum is greater than the combined transverse diameter of the upper ends of the crowns, thereby permitting said drum to be freely lifted from the container without affecting or disturbing said crowns.

The gas supply pipe 17 communicates through the port 17' in the web 3' with the annular gas chamber 5, the incoming gas thereby encircles the container 4 and retains the sealing oil at substantially an even temperature regardless of climatic changes. The gas after passing through the tube 9 enters the valve mechanism 11 and from thence passes to the outlet pipe 18 to its point of use.

Secured below the top 19 to the casing is a hanger 20 provided axially with a journal 20' and journaled therein is a worm 21, rotary movement being imparted to the worm through the medium of the link 22 connected with the valve actuating rod 23. Supported

upon the hanger 20 is a bracket 24 and journaled therein is a shaft 25 to which is fixed the worm wheel 26 adapted to mesh with the worm 21 to impart rotary movement to said shaft which in turn actuates any well known form of registering mechanism.

To vary the inclination of the drum 13, the journal 20^a is threaded in the hanger 20 and is raised or lowered by turning the knurled wheel 30. It will readily be seen that this action varies the horizontal distance between the ends of the link 22 and correspondingly changes the axial inclination of the drum 13. When the proper adjustment is made it is locked by the nut 31.

In Figure 4, the modified form of the invention, the sealing oil container 27 is formed from glass, the conducting tube 28 and crowns 29 being molded integral with said container.

It will be obvious that any foreign particles which may enter the annular chamber 5 with the incoming gas will settle upon the bottom of the casing 1 and in the compartment 7. This foreign matter may be readily removed upon removing the drum 13 and inverting the casing 1 and since the bottom 6 of the container is concave the foreign matter will readily enter the tube 9 when the casing is inverted.

This application constitutes a substitute for my abandoned application, Serial Number 688,141 filed January 24, 1924.

What is claimed is:

1. A gas meter comprising a casing, a sealing liquid container located in the casing and spaced from the walls of the latter to provide

a gas circulating chamber between the walls of the casing and the walls of said container, a gas inlet communicating with said chamber and a gas outlet formed with said casing and arranged in communication with the interior of said container. 40

2. A gas meter comprising a casing, an inwardly directed flange at the upper end of said casing, a sealing liquid container extending into the casing and spaced from the latter by means of said flange to provide a gas circulating chamber between the walls of the casing and the walls of said container, a gas inlet entering said chamber, and a gas outlet 50 having communication with said container. 45

3. A gas meter comprising a casing, a sealing liquid container extending into the casing, a lateral extending flange between the casing and the container and arranged to confine the container within said casing in a spaced relationship therefrom to provide a gas circulating chamber around said liquid container, a gas inlet entering said chamber, and a gas outlet having communication with 60 said container. 55

4. A meter of the class described comprising a casing, a sealing oil container located in the casing and having a plurality of crowns carried thereby, a drum having a plurality 65 of measuring pockets for cooperation with the crowns, the open end of said drum being greater in diameter than the combined diameter of the crowns to permit said drum to be freely disengaged from said crowns. 70

In testimony whereof I affix my signature.
HOMER J. WADDELL.
